UNITED STATES PATENT OFFICE.

DAVID B. MACDONALD, OF DAVENPORT, IOWA.

MATCH BOX.

Application filed December 4, 1920, Serial No. 428,262. Renewed May 24, 1922. Serial No. 563,388.

To all whom it may concern:

Be it known that I, DAVID B. MACDONALD, a citizen of the United States, residing at Davenport, in the county of Scott and State 5 of Iowa, have invented a new and useful Improvement in Match Boxes, of which the following is a specification.

My invention relates to improvements in match boxes which are designed to contain 10 matches having a head upon each of their ends, and the object of my improvement is to provide a match box having means for breaking off the charred end of a match after it has been lighted and used, thus to 15 preserve the remnant clean and to enable the user to dispose of the charred end before replacing the clean remnant in the box, thus preserving the unused matches within the box free from exposure to the risk of becoming soiled by contact with the charred 20 portion of used matches.

I attain these objects by the mechanism illustrated in the accompanying drawing, in which—

25 Figure 1 is a perspective view of the match box showing the device attached and in position.

Fig. 2 is a perspective view of the breaking device.

30 Fig. 3 is a perspective view showing the hole and surrounding perforations in the outside box.

Fig. 4 is an inside view of a section of the outside box disclosing the perforation and 35 manner of attachment of the breaking device and in dotted lines the position and form of the breaking device when attached.

Fig. 5 is a broken portion of the inner portion of the box.

40 Similar numerals refer to similar parts throughout the several views.

An ordinary match box having the enveloping cover or case and box forms the frame work of my invention.

45 Near the end and preferably upon one of the narrower sides of the box-case 1, I provide a hole 5, having a right angular diamond pointed off-set 5^a pointing downward as shown in Fig. 3, and having suitably arranged about and adjacent the hole 5, four perforations 4, suited to receive respectively the clamp lugs 11 of breaking device 8.

50 Breaking device 8 is a plate composed of any hard substance such as fiber or metal and in one of its sides spaced to the side of its center is provided a hole 10 having a

downwardly pointed off-set 10^a, and for the purpose of securing the same to the box, also having at each of its corners clamp lugs 11, but such breaking device may be secured to 55 the box by any other suitable means such as rivets or glue, not shown.

In mounting, the breaking device is attached to box 1, in such way that clamp lugs 11 are inserted in the perforations 4 of the 60 box-case, with hole 10 of the plate fitting conformably over hole 5 of the box-case 1, when the points of clamp lugs 11 are turned down upon the inside of box-case 1, as indicated in Fig. 4, securing the breaking device 8 firmly to the box-case 1.

The holes 5 and 10 provided with the pointed off-set are so provided for the purpose of admitting the insertion of the burnt end of a match. In use the box, Fig. 5, is 65 slid partly open in the case 1, past hole 5, and the match end inserted in the hole made by conjunction of holes 5 and 10, when with a slight side and downward motion of the outward end of the match it will be found 70 that the charred end of the match will be easily broken off, falling outside of box, Fig. 5.

75 For the purpose of breaking the ends off matches when holding the box in different 80 positions with the box Fig. 5 securely enclosed in case 1, I have provided an outwardly disposed corrugated tapering pocket 9 in a side, and a similar one 9^a in the end, of breaking device 8, each so formed that 85 when breaking device 8 is attached securely to the side of box-base 8 as shown in Fig. 1, and a match end is inserted therein slight side pressure by the hands upon the match 90 will break the charred end of the match off. 95

It will be observed that the corrugations 9 and 9^a of plate 8 are made suitably large and with their pointed ends sufficiently open that the charred end of the match when 100 broken off will fall freely out without clogging the corrugation.

I claim:

1. In combination with a match box having a match-box case, the match-box case having a hole in one of its sides; the hole having a downwardly pointed off-set; a match-box case having a match breaking device outwardly secured by suitable means to one of its sides; said match breaking device having a hole provided with a downwardly pointed off-set in its surface stationed adjacent one of its sides conformable 105 110

to the hole in the box case, multiple corrugate means in the side and end of said match breaking device, clamp lug means for securing said match breaking device to the box case; perforations suitably conformable to the clamp lugs of said match breaking device, provided in the side of said box case, all for the purposes specified.

2. In a match box having a match-box case provided with open ends, said match-box case having in one of its sides a hole provided with a downwardly pointed off-set, said hole positioned suitably for alignment with a similar hole provided in a breaking device when said breaking device is securely mounted upon said box; a breaking device having hole means therein secured to the match-box case in such manner that the hole means of the breaking device fits conformable to the hole means provided in the match-box case.

3. In a match box having a match-box case provided with open ends, and a hole having a downwardly pointed offset in one of its sides, suitable for alignment with similar hole means provided in a breaking device, when secured thereto, perforations in one of its sides adjacent the hole therein, the perforations suitable to receive the lugs of a breaking device, the breaking device secured to said match-box case on the side containing the hole, by clamp lug means clamped through perforations in such side.

4. In a match box having a match-box case provided with an open end, hole means in one of its sides and a breaking device having hole means disposed near its center,

the breaking device secured by lug means to the side of the box case in such manner that the hole of the breaking device fits conformably to the hole means in such side, said breaking device having multiple corrugations; the breaking device having one corrugation opening upwardly from near its center, and another corrugation opening at right angles from the other corrugation, each of said corrugations tapering closely toward the center of the breaking device, their inward ends approaching each other at right angles, all for the purposes specified.

5. In a match box having a match-box case provided with an open end, hole means in one of its sides and a breaking device having hole means disposed in its surface, the breaking device secured by any suitable means to the side of the box case in such manner that the hole of the breaking device fits conformably to the hole means in such side; said breaking device secured by suitable means to such box case; the breaking device having multiple corrugations opening outwardly, one of the corrugations opening upwardly from near the center, another of the corrugations opening horizontally from near its center, each of said corrugations tapering closely toward the center of the breaking device, with their inward ends approaching each other at right angles, all for the purposes specified.

DAVID B. MACDONALD.
